Primary Examiner—James Gandy*Assistant Examiner*—Linda Brooks*Attorney, Agent, or Firm*—Price, Heneveld, Cooper, DeWitt & Litton[57] **CLAIM**

The ornamental design for a freestanding modular display and divider wall, as shown and described.

DESCRIPTION

FIG. 1 is a front perspective view of a freestanding modular display and divider wall;

FIG. 2 is an end elevational view thereof, showing two adjacent sides and the end toward which they converge;

FIG. 3 is a top plan view thereof; and,

FIG. 4 is a bottom plan view thereof.

The end opposite that shown in FIG. 2 is flat and unornamented.
